UNITED STATES PATENT OFFICE.

WALTER F. VAN GUYSLING, OF ALBANY, NEW YORK.

AUTOMATIC OILER.

1,212,714.

Specification of Letters Patent. Patented Jan. 16, 1917.

Application filed June 3, 1915. Serial No. 31,821.

To all whom it may concern:

Be it known that I, WALTER F. VAN GUYSLING, a citizen of the United States of America, and a resident of Albany, county of Albany, and State of New York, have invented certain new and useful Improvements in Automatic Oilers, of which the following is a specification, reference being had to the accompanying drawings, forming a part thereof.

My invention relates to automatic oilers and has special reference to such as are operatively connected to and regulated by, the machines with which they are utilized.

One object of my invention is to provide a reliable and effective device of the aforesaid character, that shall be particularly adapted to supply oil to the cylinder of an engine.

Another object is to provide a relatively simple and particularly positive driving connection for materially reducing the speed of the driven member relative to the driving member.

Another object is to provide, in an oiler of the class above indicated, means for automatically stopping the action of the oiler when the oil is substantially exhausted from the oil chamber of the device, and a releasing mechanism which shall prevent the resetting and further advancement of the mechanism until the oil chamber has been retracted for refilling.

Another object is to provide a simple and readily detached connection adapted to be interposed between reciprocating and oscillatory members.

Other objects and advantages of my invention will be set forth hereinafter, and in order that my invention may be thoroughly understood I will now proceed to describe the same in the following specification and then point out the novel features thereof in appended claims.

Referring to the drawings: Figure 1 is a side elevation with the nozzle broken away and shown in section, of an automatic oiler arranged and constructed in accordance with my invention. The nozzle is shown in front elevation in Fig. 2. Fig. 3 is a sectional elevation of the body of the mechanism, drawn to a larger scale. The same mechanism is shown in plan view in Fig. 4. Fig. 5 shows a portion of the driving connection between the engine and the oiler. Fig. 6 is a sectional elevation taken on the line 6-6 of

Fig. 4. Figs. 7 and 8 are sectional views of one of the driving connections, taken respectively on the lines 7-7 and 8-8 of Fig. 4. Fig. 9 is a sectional plan view, taken on the line 9-9 of Fig. 3, the same parts being shown in sectional elevation in Fig. 10 which is taken on the line 10-10 of Fig. 9. Fig. 11 is a sectional elevation on the line 11-11 of Fig. 10. Fig. 12 is a detail view of the rocking pawl taken on the line 12-12 of Fig. 9. Fig. 13 is a sectional detail taken on the line 13-13 of Fig. 9. Figs. 14 and 15 are sectional plan views taken respectively on the lines 14-14 and 15-15 of Fig. 3. Fig. 16 is a sectional detail taken on the line 16-16 of Fig. 14. Fig. 17 is a sectional elevation on the line 17-17 of Fig. 3. Fig. 18 is an elevation of the lower end of the mechanism taken at right angles to Fig. 1. Fig. 19 is a sectional bottom plan view taken on the line 19-19 of Fig. 3.

The oiler comprises, in general, a stationary bracket, a vertical tube secured thereto and extending downwardly therefrom, a drum rotatively mounted on the tube which is provided with a collar for the purpose, and a yoke or cup carrier mounted to slide within the drum and screwed onto the tube so that the elevation of the cup is adjusted by turning the drum and the cup carrier. Furthermore, a piston is located near the lower end of the tube and is fitted into the cup which constitutes a movable cylinder cooperating with the stationary piston. A ratchet disk is rotatively mounted at the top of the drum and an oscillating ring is similarly mounted above the ratchet on the tube. The ring is operatively connected to the reciprocating parts of the engine or machine to be lubricated, so that an oscillation of the ring and a rod which is connected thereto, is effected. A pawl is mounted on the rod and is adapted to coöperate with the ratchet to produce a rotative movement thereof in one direction, a brake being provided to prevent the backward movement thereof. The ratchet has an eccentric cam surface which coöperates with, and is adapted to oscillate, a pivoted arm on which another pawl is mounted. The arrangement of parts is such that the radial pawl carrying arm is oscillated about its pivot by the rotative movement of the ratchet. The last-named pawl, which obviously is actuated at a very slow rate of speed relative to the first-named pawl, coöperates with ratchet

teeth on the drum and produces a very slow rotative movement of the latter. An adjustable weight device is adapted to either press the pawl into engagement with the 5 ratchet teeth on the drum or to hold it out of engagement therewith, depending upon the position in which it is set. The tube on which most of the parts of the device are mounted is provided with a check valve at 10 its lower end within the cup and is connected at its upper end to the discharge nozzle of the device which is located in the feed pipe of the engine.

Having now outlined the mechanism of 15 my invention, I will describe it in detail with reference to the drawings, as follows: 20 indicates a stationary bracket which may be secured by bolts 21 or some other suitable means, to a vertical supporting surface 22. The bracket has an arm 23 provided with an enlargement 24, and a relatively short bifurcated projection 25. The enlargement 24 has a tapped hole 26 through which a screw-threaded hollow stud or tube 27 extends. The bifurcated projection 25 is also perforated to receive a pivot pin 28. The tube 27 is rigidly affixed in position by a lock nut 29 which is screwed onto the tube at its upper end against the enlargement 24 and is held against turning by a pin 30. The tube has a collar 31 at a fixed distance below the arm 23, which supports a drum 32. The drum is partially closed at 30 its upper end and has a bearing projection 33 which fits onto the tube above the collar 31. An oscillating ring 34 is mounted on the tube between the bearing 33 and the enlargement 24. Rotatively mounted on the bearing 33 is a ratchet 35 having a plurality 35 of concentric sets of ratchet teeth 36 on its plane top surface and an eccentric hub 37 having a cylindrical cam surface 38. The number of ratchet teeth in each set is different for purposes of adjustment. The oscillating member 34 has a tangential hole 39 through which a rod 40 extends, the position of the rod being fixed as desired, by a set screw 41. Adjustably mounted on the rod (see Figs. 4 and 5) is a pawl 42 comprising a central hub 43 which may be fixed in any suitable position by a set screw 44, a relatively stationary arm 45 which extends outwardly from the hub 43 and a pawl arm 48 adjacent to the stationary arm 45 40 having a bifurcated hub 49 pivoted on the rod 40. The arm 45 and the pawl arm 48 are provided with recesses 46 constituting seats for a compression spring 47 which tends to force the arms apart. The hubs 43 and 49 have co-operating lugs 50-50' which are arranged so as to limit the movement of the pawl arm 48 relative to the stationary arm 45, and consequently permit the pawl to be adjusted as a unit without 45 danger of losing the spring even when the

pawl arm is not in position to engage the teeth of the ratchet.

As clearly shown in Fig. 4, the pawl arm is adapted to engage any one of the plurality of rows of ratchet teeth 36 of the 70 ratchet 35. The rod 40 is adapted to be oscillated, together with the ring 34 by the machine or engine, with which the oiler is to be used, for example,—the rod 51 shown in Fig. 4, may be connected to be reciprocated in response to the movement of an engine valve gear and is connected to the rod 40 in any suitable way, the connection which I prefer being shown in Figs. 4, 7 and 8, to which special reference may now be had. 80

The rod 40 is provided with a collar 52 near its outer end and is screw-threaded at 53 to receive a nut 54. Between the nut and the collar 52 is rotatively supported a trunnion block 55 having oppositely extending 85 trunnions 56. A stud 57 is screwed onto the end of the rod 51 and supports a yoke composed of a pair of angle blocks 58 and 59 having holes 60 through which a screw-threaded projection 61 of the stud 57 extends (one of the holes 60 being tapped and one a clearance hole, in accordance with usual practice), and holes 62 to receive the trunnions 56. A connection is thus established which permits the necessary freedom 95 of movement of the rod 51, with the result that the reciprocatory motion of the engine parts is translated into an oscillatory movement of the rod 40 and the ring 34.

The ratchet disk 35 has a circumferential 100 groove 124 which receives a brake band, preferably comprising a piano wire ring 125. One end of the ring extends tangentially into a hole 126 in a lug 130 of the bracket 20 and is locked in position by a 105 set screw 127. A washer 128 is mounted to slide on the tangential end of the wire 125 and a helical spring 129 is interposed between the washer and the adjacent surface of the lug 130. The opposite end of the wire is 110 bent around the tangential end forming a loop 131 adjacent to the washer 128, the arrangement of parts being such that the spring tends closely to draw the wire around the ratchet disk and prevent a counterclockwise rotation of the disk. However, the disk is free to rotate in the opposite direction because the friction between the disk and the wire is such as to cause the loop 131 to compress the spring 129 and loosen the 115 band.

The rod 40 may obviously extend at any suitable angle from the bracket and the rod 51 may bear various relations to the rod 40 and evidently the oiler may be connected to 125 be operated by machines of various sizes and types by merely effecting simple adjustments.

Extending between the parts of the bifurcated projection 25 and pivotally connected 130

thereto by the pin 28, is a pawl carrier 63 having a central enlargement which is provided with an elliptical hole 64 and is interposed between the ratchet disk 35 and the top of the drum 32, the cam projection or hub 37 of the ratchet extending into the elliptical hole 64. The arrangement of parts is such that when the ratchet 35 is rotated the cam surface 38 of the projection 37 causes the pawl carrier 63 to oscillate about the pin 28 as a pivot. Beyond the ratchet 35 the carrier 63 has a hub projection 65 having a suitable hole 66 to receive a vertical pivot pin 67. Laterally spaced from the hub projection 65 is a lug 68 which lies in a vertical plane as shown in Figs. 4 and 9 and supports a horizontal pin 69, as clearly shown in Fig. 11. The adjacent surface of the hub 65 has a recess 70 in which one end of the pin 69 is seated, a weight arm 71 and a crescent-shaped rocking pawl 72 being pivotally supported on the pin and disposed between the hub 65 and the lug 68. The hub 65 is further provided with a recess 73 (see Figs. 3 and 11) into which extends a laterally extending projection 74 from the rocking pawl 72. Pivotally mounted on the pin 67 is a pawl 75 having a bifurcated hub. This pawl 75 has a pair of oppositely faced lug projections 76 and 77 which are shown in section in Fig. 10 and which are respectively actuated as hereinafter explained, to throw the pawl into or out of engagement with a set of ratchet teeth 78 with which the drum 32 is provided.

The weight arm 71 has a slot 79 through which the pin 69 extends and which permits the arm to be adjusted into one of two positions shown respectively in full and dotted lines in Fig. 10. It has a laterally extending lug 80 which is adapted to engage one of the horns 81 of the crescent-shaped rocking pawl 72 when it is adjusted to the position shown in full lines in Fig. 10.

The crescent-shaped pawl 72 is free to oscillate only within certain limits which are determined by the engagement of the lateral projection 74 with the ends of the recess 73 in the hub 65, but the weight of the arm 71, which is enlarged at its outer end, and tends to swing the arm downwardly, is applied through the pawl 72 to the ratchet pawl 75, the opposite horn 82 of the crescent-shaped pawl 72 being in engagement with the lug 76 of the pawl 75 (see Figs. 4, 9 and 10). When the weight arm is adjusted to its opposite position or is merely forced outwardly as hereinafter explained, and permitted to drop, the lateral projection 80 is released from the horn 81 of the rocking pawl and comes into engagement with the lug 77 of the pawl 75. The action of the weight now tends to force the pawl 75 out of engagement with the ratchet teeth 78 while in the opposite position the weight

tends to move the pawl 75 into engagement therewith. Thus it is evident that the weight mechanism constitutes a simple means, which is independent of any spring, for either pressing the pawl into engagement with the ratchet teeth or holding it away from the teeth.

The position of the weight may obviously be changed by hand either to set or release the pawl, but when set it is furthermore adapted to be automatically released. This is accomplished by a pawl 83 which is pivotally supported by a pin 84 from a downwardly extending projection 85 of the oscillating pawl carrier 63. The pawl 83 has an upwardly extending arm 86 which is adapted to engage the inner end of the weight arm 71 as shown in Fig. 10. It furthermore, has a downwardly extending release arm 87 which extends close to the outer surface of the drum 32 and near to a ring 88 which is mounted thereon. The arrangement of parts is such that when the ring, as hereinafter explained, is moved upwardly, it swings the pawl 83 about the pin 84 as a pivot and forces the weight arm outwardly so as to release it and permit it to fall from its full line position to its dotted line position in Fig. 10. In other words, when the ring is elevated it releases the pawl 75 from the ratchet teeth 78 since this pawl is controlled, as already explained, by the weight 71.

The drum 32 is provided with a pair of vertical slots 89 (see Fig. 16) through which extend inwardly projecting pins 90 from the ring 88. The pins normally rest at the bottom ends of the slots and hold the ring from falling.

The drum is provided with a pair of opposite vertically-grooved inwardly-extending ribs 91 which are arranged in quadrature relation relative to the pins 90 (see Fig. 14) and they are adapted to provide guideways for a frame or yoke 92 which is slidably mounted within the drum as clearly shown in Figs. 3 and 14. The yoke comprises a pair of spaced parallel side bars 93, a cross-bar 94 at the bottom having one or more handle projections 95, and a hub 96 at the top. The hub has a pair of laterally projecting extensions 97 at right angles to the plane of the side bars, which are adapted to engage the pins 90 when the yoke is sufficiently elevated. They are at all times in vertical alignment with the pins. The hub 96 has a central tapped hole 98 (see Figs. 3 and 16) through which the screw-threaded tube or hollow stud 27 extends.

The arrangement of parts is such that when the drum 32 and the yoke 92, which have a telescoping arrangement but cannot rotate independently of each other, are turned about the tube 27 as an axis, the yoke, by reason of its screw threaded rela-

tion to the tube is slowly elevated or lowered within the drum. The top of the yoke is preferably provided with oil grooves 100 which may be supplied through a hole 101 in a drum, to lubricate the coöperating threaded parts.

The yoke 92 constitutes a carrier for a cylindrical cup 102 which is an oil or other lubricant container and acts like a movable cylinder with reference to a stationary piston 103 which is secured to the lower end of the tube or hollow stud 27.

The piston may be constructed in any suitable manner and preferably has an annular projection 104 forming a recess in which is disposed a screen 105 held in place by a pin 106. The piston member also has a screw-threaded tubular projection 107 which is screwed into a tapped hole 108 in the lower end of the tube 27. Within the tubular projection 107 is a check valve 109 pressed closed by a spring 110, the spring being backed by a pin 111. The piston furthermore, comprises a ring 145 secured to the lower end of the tube 27 and a flexible packing ring 146 which is clamped between the body of the piston and the ring 145, the body being provided with a bead 147 which grips the packing ring and makes an oil-tight joint between the piston projection 107 and the tube 27.

The cup may be mounted on the yoke 92 in any suitable way but for convenience in removing and replacing the cup which is necessary for refilling, I have provided a transverse dovetailed groove 112 in the base of the cup, which coöperates with the dovetailed head 113 of a stud 114. This stud extends through a suitable hole 115 in the cross-piece 94 of the yoke and has a nut 116 secured to its lower end. In order to permit the yoke to rotate freely with reference to the cup and stud, ball bearings are provided as indicated at 117.

For convenience in centering the cup longitudinally of the head 113, the ends of the groove 112 are mounted as shown at 118, and coöperate with a bow spring 119 which is secured by means of a screw 121, in a groove 120 in the dovetailed head 113. The nut 116 is held from turning by a pin 122 and the screw 121 is held from turning by a pin 123. Side bars 93 of the yoke 92 are preferably graduated as clearly shown in Fig. 18, to indicate the amount of lubricating fluid remaining in the cup, as more fully explained in connection with the operation of the device.

It is evident that the tube communicates with the cup, the check valve being so arranged as to permit fluid to be forced from the cup upwardly through the tube. The upper end of the tube is connected by a suitable pipe 132 to a discharge nozzle.

While my device is of course adapted to

be used with nozzles of various kinds, the kind selected being dependent upon the machine to be oiled and various other conditions of service, I have shown and described what I believe to be a particularly advantageous form of nozzle for discharging the oil in a finely divided state into the feed pipe of a steam engine.

Referring to Figs. 1 and 2, 133 indicates the steam pipe, the arrow 134 indicating the direction of flow of steam therein. Extending into the pipe 133 is a nozzle 135 having a screw-threaded shank 136 connected at its outer end by a union 137 to the pipe 132, and set in a plug 138. The nozzle itself is in the form of a bent tube flattened at its open end as shown at 139 and having an opening 140 back of the discharge end of the convex side of the bend in the tube. The nozzle is set in the pipe 133 with the flattened discharge end 139 in the center of the pipe and extending in the direction of the arrow 134,—that is to say, in the direction of the flow of steam in the pipe, the hole 140 being so located as to receive a certain amount of steam sufficient to break up the oil so that it is discharged into the steam pipe in a finely divided state.

The operation of the apparatus is as follows:—Assuming that the cup 102 is partially filled with lubricating fluid and that the rod 51 is connected to a reciprocating part of an engine, the movement of the rod 51 will produce an oscillatory movement of the ring 34 by reason of the connection established through the rod 40 between the ring and the rod 51. The pawl 42 will consequently be oscillated about the center of the tube 27 as an axis. The pawl, as already explained, may be set to coöperate with any one of the sets of ratchet teeth 36 (three sets being illustrated), and will produce a step by step rotative movement of the ratchet, the speed of movement depending upon the row of ratchet teeth engaged by the pawl and upon the stroke of the rod 51. The ratchet is prevented from being backwardly rotated when the pawl oscillates in a clockwise direction (see Fig. 4) by the brake wire 125, the action of which has already been explained.

The rotation of the ratchet 35 produces an oscillation of the pawl carrier 63, by reason of the engagement of the eccentric cylindrical projection 37 with the hole 64 in the carrier. It is evident that the pawl carrier 63 is oscillated slowly since it is moved over and back only once for each revolution of the ratchet 35. The pawl 75 which is pivotally mounted on the pawl carrier and engages the ratchet teeth 78 of the drum 32, serves to produce a very slow rotative movement of the drum.

Since the yoke 93 is mounted in guideways in the drum it rotates with the drum and by

reason of the fact that it is screwed onto the externally-threaded lower end of the tube 27, it acts like a traveling nut and moves upwardly as the drum is turned. As the 5 yoke moves upwardly it of course carries the cup 102 with it and since the piston 103 is stationary, being affixed to the lower end of the stationary tube 27, the lubricating fluid contained in the cup is forced upwardly through the screen 105 and into the tube 27, lifting the check valve 109 in opposition to the spring 110.

Of course the cup advances very slowly but since the lubricating fluid is practically 15 non-compressible it is very positively forced upwardly and gradually fills the tube 27 and flows through the pipe 132, being finally forced outwardly through the nozzle 139. If it is assumed that steam is flowing at 20 a rapid rate in the direction of the arrow 134 in the feed pipe 138, it will enter the opening 140 in the nozzle and will be discharged with the lubricating fluid from the flattened end of the nozzle, the steam mingling with 25 and breaking up the fluid so that it is discharged into the center of the pipe in a finely divided state and is carried into the engine cylinder where it is utilized for lubricating the cylinder walls.

30 Should the flattened discharge opening of the nozzle become clogged the oil will be forced out through the opening 140 and since it will enter the center of the pipe 137 in any event, it will be carried along by the 35 steam and do its work.

When the oil is nearly exhausted from the cup, the piston being near the bottom, the lugs 97 of the yoke 92 attain a sufficient height to engage the pins 90 which are attached to the ring 88, and a slight further upward movement of the yoke raises the ring 88 which in turn actuates the pawl 83. This pawl when actuated throws the weight arm 71 outwardly and releases the lateral 40 lug 80 from the horn 81 of the rocking pawl 72. Thus, the weight arm is released and falls into its lower position, as shown in broken lines in Fig. 10 and the lateral lug 80 engages the lug 77 of the pawl 75. This 45 pawl is released in consequence and occupies an inoperative position. Although the oscillating pawl carrier 63 moves in response to the moving parts of the engine or machine to which the lubricant is supplied, the motion is not transmitted to the drum 50 and the oiler is inoperative. The height of ring 88 is then such that the weight arm 71 cannot be moved back to its former position. By this means all danger of injuring the 55 parts of the device is avoided and furthermore the weight arm 71 acts as an indicator to show when the oil container should be refilled. In fact, the graduations which are found on the side bars 93 of the yoke 60 92, as shown in Fig. 18, are intended to

warn an attendant when to refill the container without waiting for the oiler to be stopped automatically. In any event, after the weight arm 71 has been thrown into its lower position, either automatically or by hand, the attendant, by means of the handle 95, turns the yoke and drum 32 in a counterclockwise direction so as to lower the yoke. This is continued until the cup is free from the piston when the cup is removed laterally, is refilled and replaced. The yoke can be lowered easily although the piston fits closely into the cup, because the ball-bearings allow the yoke to turn free from the cup which merely slides off of the piston and does not rotate. The yoke is then turned by hand until the piston is well seated in the cup and engages the surface of the fluid therein, and then it is only necessary to reset the weight arm 71 in its elevated position by swinging it upwardly and pushing it in, so that the lug 80 engages the horn 81, to reestablish the automatic oil feeding operation of the device.

By reason of the fact that my oiler is 90 very positive in its action and is particularly unlikely to become disarranged, it is well adapted for use in lubricating the cylinders of a locomotive although, of course, it is not limited to any particular 95 class of service.

Various structural modifications may be effected within the spirit and scope of my invention, but I intend that only such limitations be imposed as are indicated in the 100 appended claims.

What I claim is:

1. An oiler comprising a piston, an outlet connected to the piston, a container adapted to coöperate with the piston, a connection comprising a ratchet and pawl, responsive to the machine to be lubricated for causing the piston to approach the bottom of the container, a weight arm pivotally supported near the pawl and adapted to be elevated to hold the pawl in engagement with the ratchet teeth and adapted when released from its elevated position to hold the pawl out of engagement with the ratchet teeth.

2. An oiler comprising a piston, an outlet connected to the piston, a container adapted to coöperate with the piston, a connection comprising a ratchet and pawl, responsive to the machine to be lubricated for causing the piston to approach the bottom of the container, a weight arm pivotally supported near the pawl and adapted to be elevated to hold the pawl in engagement with the ratchet teeth and adapted when released from its elevated position to hold the pawl out of engagement with the ratchet teeth; and a trigger dependent upon a predetermined relative position of the piston and container for releasing the arm.

3. An oiler comprising a piston, an outlet connected to the piston, a container adapted to coöperate with the piston, a connection comprising a ratchet and pawl, responsive to the machine to be lubricated for causing the piston to approach the bottom of the container, a weight arm, and a crescent-shaped rocker coaxially pivoted near the pawl, said rocker being adapted to hold the pawl in engagement with the ratchet teeth when the weight arm is fulcrumed on one horn of the rocker, and means for releasing the arm from the rocker when the piston approaches the bottom of the container.
- 15 4. An oiler comprising a piston, an outlet connected to the piston, a container adapted to coöperate with the piston, a connection comprising a ratchet and pawl, responsive to the machine to be lubricated for causing the piston to approach the bottom of the container, a weight arm, a crescent-shaped rocker coaxially pivoted near the pawl, said rocker being adapted to hold the pawl in engagement with the ratchet teeth when the weight arm is fulcrumed on one horn of the rocker, and a trigger dependent upon a predetermined relative position of the piston and container for releasing the arm.
- 25 5. An oiler comprising a piston, an outlet connected to the piston, a container adapted to coöperate with the piston, a connection comprising a ratchet and pawl, responsive to the machine to be lubricated for causing the piston to approach the bottom of the container, a pivoted weight arm, a crescent-shaped rocker coaxially pivoted with the weight arm and adapted to hold the pawl in engagement with the ratchet teeth when the weight arm is fulcrumed on one horn of the rocker, said weight arm being adapted to act directly upon the pawl to hold it out of engagement with the ratchet teeth when the weight arm is released from the rocker horn.
- 35 45 6. An oiler comprising a piston, an outlet connected to the piston, a container adapted to coöperate with the piston, a connection comprising a ratchet and pawl, responsive to the machine to be lubricated for causing the piston to approach the bottom of the container, a pivoted weight arm, a crescent-shaped rocker coaxially pivoted with the weight arm and adapted to hold the pawl in engagement with the ratchet teeth when the weight arm is fulcrumed on one horn of the rocker, said weight arm being adapted to act directly upon the pawl to hold it out of engagement with the ratchet teeth when the weight arm is released from the rocker horn, and a trigger dependent upon a predetermined relative position of the piston and container for releasing the weight arm.
- 50 55 60 65 7. An oiler comprising a piston, an outlet connected to the piston, a container adapted to coöperate with the piston, a con-

nection comprising a ratchet and pawl, responsive to the machine to be lubricated for causing the piston to approach the bottom of the container, a pivoted weight arm, a crescent-shaped rocker coaxially pivoted with the weight arm, said weight arm being provided with a lateral projection adapted to engage one horn of the rocker and to cause the rocker to act upon and hold the pawl in engagement with the ratchet teeth.

8. An oiler comprising a piston, an outlet connected to the piston, a container adapted to coöperate with the piston, a connection comprising a ratchet and pawl, responsive to the machine to be lubricated for causing the piston to approach the bottom of the container, a pivoted weight arm, a crescent-shaped rocker coaxially pivoted with the weight arm, means for limiting the oscillatory movement of the rocker on its pivot, said weight arm being provided with a lateral projection adapted to engage one horn of the rocker and to cause the rocker to act upon and hold the pawl in engagement with the ratchet teeth.

9. An oiler comprising a piston, an outlet connected to the piston, a container adapted to coöperate with the piston, a connection comprising a ratchet and pawl, responsive to the machine to be lubricated for causing the piston to approach the bottom of the container, a pivoted weight arm, a crescent-shaped rocker coaxially pivoted with the weight arm, said weight arm being provided with a lateral projection adapted to engage one horn of the rocker and to cause the rocker to act upon and hold the pawl in engagement with the ratchet teeth and said weight arm being adjustable to release its lateral projection from the horn of the rocker and being adapted to act when released upon the pawl directly to hold it out of engagement with the ratchet teeth.

10. An oiler comprising a piston, an outlet connected to the piston, a container adapted to coöperate with the piston, a connection comprising a ratchet and pawl, responsive to the machine to be lubricated for causing the piston to approach the bottom of the container, a pivoted weight arm, a crescent-shaped rocker coaxially pivoted with the weight arm and adapted to hold the pawl in engagement with the ratchet teeth when the weight arm is fulcrumed on one horn of the rocker, said weight arm being adapted to act directly upon the pawl to hold it out of engagement with the ratchet teeth when the weight arm is released from the rocker horn, a trigger dependent upon a predetermined relative position of the piston and container for releasing the weight arm, and a trigger for releasing the arm from the rocker.

11. An automatic oiler comprising a stationary tubular piston rod, a piston at its

- lower end, a check valve in the tubular rod near the piston, a drum rotatively mounted on the piston rod, a yoke slidably mounted within the drum and screwed onto the stationary piston rod, a cylindrical container mounted on the yoke and adapted to co-operate with the piston, and means dependent upon the moving parts of the machine to be lubricated for turning the yoke to raise the cylindrical container and force the lubricating fluid therefrom through the check valve and through the hollow piston rod.
12. An automatic oiler comprising a stationary tubular piston rod, a piston at its lower end, a check valve in the tubular rod near the piston, a drum rotatively mounted on the piston rod, a yoke slidably mounted within the drum and screwed onto the stationary piston rod, a cylindrical container mounted on the yoke and adapted to co-operate with the piston, and a ratchet and pawl mechanism for slowly turning the drum to elevate the container and force the lubricating fluid therefrom through the check valve and through the hollow piston rod.
13. An automatic oiler comprising a stationary tubular piston rod, a piston at its lower end, a check valve in the tubular rod near the piston, a drum rotatively mounted on the piston rod, a yoke slidably mounted within the drum and screwed onto the stationary piston rod, a cylindrical container mounted on the yoke and adapted to co-operate with the piston, an independently rotatable ratchet, an oscillating pawl carrier adapted to be oscillated by a rotative movement of the ratchet, a pawl mounted on the carrier and adapted to actuate the drum, and means dependent upon the machine to be lubricated for actuating the ratchet.
14. An automatic oiler comprising a stationary tubular piston rod, a piston at its lower end, a check valve in the tubular rod near the piston, a drum rotatively mounted on the piston rod, a yoke slidably mounted within the drum and screwed onto the stationary piston rod, a cylindrical container mounted on the yoke and adapted to co-operate with the piston, a ratchet rotatively mounted on the drum, a ring rotatively supported adjacent to the ratchet and adapted to be oscillated by the movement of the machine to be lubricated, a pawl mounted to oscillate with the ring and adapted to produce a rotative movement of the ratchet, a pawl carrier adapted to be oscillated by the rotative movement of the ratchet, a pawl mounted on the pawl carrier, and ratchet teeth on the drum adapted to be actuated by the pawl for producing a gradual rotative movement of the drum.
15. An oiler comprising a stationary piston, an outlet connected to the piston, a container for lubricating fluid adapted to co-operate with the piston, a rotatable member having a fixed relation to the piston, a carrier slidably mounted in said member and adapted to turn with it, and a stationary screw-threaded support adapted to co-operate with the carrier for moving the container relative to the piston, whereby the fluid in the container is forced through the outlet pipe.
16. An oiler comprising a stationary piston, an outlet connected to the piston, a container for lubricating fluid adapted to co-operate with the piston, a rotatable member having a fixed relation to the piston, a carrier slidably mounted in said member and adapted to turn with it, and a stationary screw-threaded support adapted to co-operate with the carrier for moving the container relative to the piston; and means dependent upon the machine to be lubricated for rotating the carrier.
17. An oiler comprising a stationary piston, an outlet connected to the piston, a container for lubricating fluid adapted to co-operate with the piston, a rotatable member having a fixed relation to the piston, a carrier slidably mounted in said member and adapted to turn with it, a stationary screw-threaded support adapted to co-operate with the carrier for moving the container relative to the piston, means dependent upon the machine to be lubricated for rotating the carrier, and means for stopping the movement of the carrier when the piston approaches the bottom of the container.
18. An oiler comprising a stationary piston, an outlet connected to the piston, a container for lubricating fluid adapted to co-operate with the piston, a rotatable member having ratchet teeth in fixed relation to the piston, a carrier slidably mounted in said member and adapted to turn with it, a stationary screw-threaded support adapted to co-operate with the carrier for moving the container relative to the piston, whereby the fluid in the container is forced through the outlet pipe, and means for stopping the movement of the carrier when the piston approaches the bottom of the container.
19. An oiler comprising a stationary piston, an outlet connected to the piston, a container for lubricating fluid adapted to co-operate with the piston, a rotatable member having ratchet teeth in fixed relation to the piston, a carrier slidably mounted in said member and adapted to turn with it, a stationary screw-threaded support adapted to co-operate with the carrier for moving the container relative to the piston, whereby the fluid in the container is forced through the outlet pipe, means for stopping the movement of the carrier when the piston approaches the bottom of the container, an actuating pawl, and means for releasing the

pawl when the piston approaches the bottom of the container.

20. An automatic oiler comprising a stationary tubular piston rod, a piston at its lower end, a drum rotatively mounted on the piston rod, a carrier slidably mounted within the drum, a cylinder adapted to contain a lubricating fluid, mounted on the carrier with the piston extending downwardly into it, and means dependent upon the moving parts of the machine to be lubricated for slowly raising the cup to force the lubricating fluid upwardly through the tubular piston rod.

15 21. An automatic oiler comprising a stationary tubular externally-threaded piston rod, a piston at its lower end, a drum rotatively mounted on the piston rod, a carrier screwed onto the piston rod and slidably
20 mounted within the drum, a cylinder adapted to contain a lubricating fluid, mounted on the carrier with the piston extending downwardly into it, and means dependent upon the moving parts of the machine to be lubricated for turning the drum and carrier to raise the cup and force the lubricating fluid outwardly through the tubular piston rod.

22. An automatic oiler comprising a stationary tubular externally-threaded piston rod, a piston at its lower end, a drum rotatively mounted on the piston rod and having ratchet teeth, a carrier screwed onto the piston rod and slidably mounted within the drum, a cylinder adapted to contain a lubricating fluid, mounted on the carrier with the piston extending downwardly into it, a pawl carrier adapted to be oscillated in response to the moving parts of the machine to be lubricated, and a pawl mounted thereon and adapted to coöperate with the ratchet teeth of the drum for producing a slow rotative movement of the drum and carrier.

23. An automatic oiler comprising a stationary tubular externally threaded piston rod, a piston at its lower end, a drum rotatively mounted on the piston rod and having ratchet teeth, a carrier screwed onto the piston rod and slidably mounted within the drum, a cylinder adapted to contain a lubricating fluid, mounted on the carrier with the piston extending downwardly into it, a pawl carrier adapted to be oscillated in response to the moving parts of the machine to be lubricated, a pawl pivotally mounted on the carrier and adapted to cooperate with the ratchet teeth of the drum, and means for releasing the pawl when the piston approaches the bottom of the cylinder.

24. An automatic oiler comprising a stationary tubular externally-threaded piston rod, a piston at its lower end, a drum rotatively mounted on the piston rod and having ratchet teeth, a carrier screwed onto

the piston rod and slidably mounted within the drum, a cylinder adapted to contain a lubricating fluid, mounted on the carrier with the piston extending downwardly into it, a pawl carrier adapted to be oscillated in response to the moving parts of the machine to be lubricated, a pawl pivotally mounted on the carrier and adapted to cooperate with the ratchet teeth of the drum, and a weight mechanism mounted on the pawl carrier for holding the pawl either in an operative or an inoperative position relative to the ratchet. 70 75

25. An automatic oiler comprising a stationary tubular externally-threaded piston rod, a piston at its lower end, a drum rotatively mounted on the piston rod and having ratchet teeth, a carrier screwed onto the piston rod and slidably mounted within the drum, a cylinder adapted to contain a lubricating fluid, mounted on the carrier with the piston extending downwardly into it, a pawl carrier adapted to be oscillated in response to the moving parts of the machine to be lubricated, a pawl pivotally mounted on the carrier and adapted to coöperate with the ratchet teeth of the drum, a weight mechanism mounted on the pawl carrier for holding the pawl either in an operative or an inoperative position relative to the ratchet, and means for automatically adjusting the weight mechanism to release the pawl when the piston approaches the bottom of the cylinder.

26. An automatic oiler comprising a stationary tubular externally-threaded piston rod, a piston at its lower end, a drum rotatively mounted on the piston rod and having ratchet teeth, a carrier screwed onto the piston rod and slidably mounted within the drum, a cylinder adapted to contain a lubricating fluid, mounted on the carrier with the piston extending downwardly into it, a pawl carrier adapted to be oscillated in response to the moving parts of the machine to be lubricated, a pawl pivotally mounted on the carrier and adapted to coöperate with the ratchet teeth of the drum, a weight arm pivotally mounted on the pawl carrier and adapted to hold the pawl in engagement with the ratchet teeth when adjusted to one position and adapted to release the pawl when adjusted to another position, and a trigger mounted on the pawl carrier for throwing the weight arm from one position to the other when the piston approaches the bottom of the cylinder.

27. An automatic oiler comprising a stationary tubular externally-threaded piston rod, a piston at its lower end, a drum relatively mounted on the piston rod and having ratchet teeth, a carrier screwed onto the piston rod and slidably mounted within the drum, a cylinder adapted to contain a lubricating fluid, mounted on the carrier with 125 130

- the piston extending downwardly into it, a pawl carrier adapted to be oscillated in response to the moving parts of the machine to be lubricated, a pawl pivotally mounted on the carrier and adapted to coöperate with the ratchet teeth of the drum, a weight arm pivotally supported on the pawl carrier on a horizontal axis and adapted to be elevated to hold the pawl in engagement with the ratchet teeth and adapted when released from its elevated position to hold the pawl out of engagement with the ratchet teeth.
28. An automatic oiler comprising a stationary tubular externally-threaded piston rod, a piston at its lower end, a drum rotatively mounted on the piston rod and having ratchet teeth, a carrier screwed onto the piston rod and slidably mounted within the drum, a cylinder adapted to contain a lubricating fluid, mounted on the carrier with the piston extending downwardly into it, a pawl carrier adapted to be oscillated in response to the moving parts of the machine to be lubricated, a pawl pivotally mounted on the carrier and adapted to coöperate with the ratchet teeth of the drum, a weight arm pivotally supported on the pawl carrier on a horizontal axis and adapted to be elevated to hold the pawl in engagement with the ratchet teeth and adapted when released from its elevated position to hold the pawl out of engagement with the ratchet teeth, and a trigger dependent upon a predetermined relative position of the piston and the cylinder for releasing the arm.
29. An automatic oiler comprising a stationary tubular externally-threaded piston rod, a piston at its lower end, a drum rotatively mounted on the piston rod and having ratchet teeth, a carrier screwed onto the piston rod and slidably mounted within the drum, a cylinder adapted to contain a lubricating fluid, mounted on the carrier with the piston extending downwardly into it, a pawl carrier adapted to be oscillated in response to the moving parts of the machine to be lubricated, a pawl pivotally mounted on the carrier and adapted to coöperate with the ratchet teeth of the drum, a weight arm, and a crescent-shaped rocker coaxially pivoted on the pawl carrier, and a trigger pivotally mounted on the pawl carrier, said weight arm having a lateral projection adapted to engage one of the horns of the rocker when elevated, the opposite horn of the rocker being in engagement with the pawl and arranged to press the pawl into engagement with the ratchet teeth.
30. An automatic oiler comprising a stationary tubular externally-threaded piston rod, a piston at its lower end, a drum rotatively mounted on the piston rod and having ratchet teeth, a carrier screwed onto the piston rod and slidably mounted within the drum, a cylinder adapted to contain a lubricating fluid, mounted on the carrier with the piston extending downwardly into it, a pawl carrier adapted to be oscillated in response to the moving parts of the machine to be lubricated, a pawl pivotally mounted on the carrier and adapted to coöperate with the ratchet teeth of the drum, a weight arm having a longitudinal slot and horizontally pivoted on the pawl carrier, the pivotal axis extending through said slot, a crescent-shaped rocker coaxially pivoted with the arm and adapted to engage the pawl with one of its horns, said weight having an offset projection adapted to engage the other horn of the rocker in an elevated position and to press the pawl through the intervention of the rocker into engagement with the ratchet teeth.
31. An automatic oiler comprising a stationary tubular externally-threaded piston rod, a piston at its lower end, a drum rotatively mounted on the piston rod and having ratchet teeth, a carrier screwed onto the piston rod and slidably mounted within the drum, a cylinder adapted to contain a lubricating fluid, mounted on the carrier with the piston extending downwardly into it, a pawl carrier adapted to be oscillated in response to the moving parts of the machine to be lubricated, a pawl pivotally mounted on the carrier and adapted to coöperate with the ratchet teeth of the drum, a weight arm having a longitudinal slot and horizontally pivoted on the pawl carrier, the pivotal axis extending through said slot, a crescent-shaped rocker coaxially pivoted with the arm and adapted to engage the pawl with one of its horns, said weight having an offset projection adapted to engage the other horn of the rocker in an elevated position and to press the pawl through the intervention of the rocker into engagement with the ratchet teeth; and a trigger pivotally mounted on the pawl carrier for releasing the arm from the rocker.
32. An automatic oiler comprising a stationary tubular externally-threaded piston rod, a piston at its lower end, a drum rotatively mounted on the piston rod and having ratchet teeth, a carrier screwed onto the piston rod and slidably mounted within the drum, a cylinder adapted to contain a lubricating fluid, mounted on the carrier with the piston extending downwardly into it, a pawl carrier adapted to be oscillated in response to the moving parts of the machine to be lubricated, a pawl pivotally mounted on the carrier and adapted to coöperate with the ratchet teeth of the drum, a weight arm having a longitudinal slot and horizontally pivoted on the pawl carrier, the pivotal axis extending through said slot, a crescent-shaped rocker coaxially pivoted with the arm and adapted to engage the pawl with one of its horns, said weight having an offset projection adapted to engage the other horn of the rocker in an elevated position and to press the pawl through the intervention of the rocker into engagement with the ratchet teeth.

one of its horns, said weight having an offset projection adapted to engage the other horn of the rocker in an elevated position and to press the pawl through the intervention of the rocker into engagement with the ratchet teeth; and a trigger pivotally mounted on the pawl carrier for releasing the arm from the rocker, said arm when released being adapted to act directly upon the pawl to hold it out of engagement with the ratchet.

33. An automatic oiler comprising a stationary tubular externally-threaded piston rod, a piston at its lower end, a drum rotatively mounted on the piston rod and having ratchet teeth, a carrier screwed onto the piston rod and slidably mounted within the drum, a cylinder adapted to contain a lubricating fluid, mounted on the carrier with the piston extending downwardly into it, a pawl carrier adapted to be oscillated in response to the moving parts of the machine to be lubricated, a pawl pivotally mounted on the carrier and adapted to coöperate with the ratchet teeth of the drum, a weight arm pivotally mounted on the pawl carrier and adapted to hold the pawl in engagement with the ratchet teeth when adjusted to one position and adapted to release the pawl when adjusted to another position, and a trigger mounted on the pawl carrier for throwing the weight arm from one position to the other when the piston approaches the bottom of the cylinder, a ring slidably mounted on the drum adjacent to the trigger, having pins extending through slots in the drum, arranged to be engaged by the carrier when the piston approaches the bottom of the cylinder and adapted to actuate the trigger.

34. An automatic oiler comprising a stationary tubular externally-threaded piston rod, a piston at its lower end, a drum rotatively mounted on the piston rod and having ratchet teeth, a carrier screwed onto the piston rod and slidably mounted within the drum, a cylinder adapted to contain a lubricating fluid, mounted on the carrier with the piston extending downwardly into it, a pawl carrier adapted to be oscillated in response to the moving parts of the machine to be lubricated, a pawl pivotally mounted on the carrier and adapted to coöperate with the ratchet teeth of the drum, a weight arm pivotally supported on the pawl carrier on a horizontal axis and adapted to be elevated to hold the pawl in engagement with the ratchet teeth and adapted when released from its elevated position to hold the pawl out of engagement with the ratchet teeth, a trigger dependent upon a predetermined relative position of the piston and the cylinder for releasing the arm, and a sliding ring mounted on the drum adjacent to the

trigger, having pins extending through slots in the drum, arranged to be engaged by the carrier when the piston approaches the bottom of the cylinder and adapted to actuate the trigger.

35. An automatic oiler comprising a stationary tubular externally-threaded piston rod, a piston at its lower end, a drum rotatively mounted on the piston rod and having ratchet teeth, a carrier screwed onto the piston rod and slidably mounted within the drum, a cylinder adapted to contain a lubricating fluid, mounted on the carrier with the piston extending downwardly into it, a pawl carrier adapted to be oscillated in response to the moving parts of the machine to be lubricated, a pawl pivotally mounted on the carrier and adapted to coöperate with the ratchet teeth of the drum, a weight arm, and a crescent-shaped rocker coaxially pivoted on the pawl carrier, a trigger pivotally mounted on the pawl carrier, said weight arm having a lateral projection adapted to engage one of the horns of the rocker when elevated, the opposite horn of the rocker being in engagement with the pawl and arranged to press the pawl into engagement with the ratchet teeth; and a sliding ring mounted on the drum adjacent to the trigger, having pins extending through slots in the drum, arranged to be engaged by the carrier when the piston approaches the bottom of the cylinder and adapted to actuate the trigger.

36. An automatic oiler comprising a stationary tubular externally-threaded piston rod, a piston at its lower end, a drum rotatively mounted on the piston rod and having ratchet teeth, a carrier screwed onto the piston rod and slidably mounted within the drum, a cylinder adapted to contain a lubricating fluid, mounted on the carrier with the piston extending downwardly into it, a pawl carrier adapted to be oscillated in response to the moving parts of the machine to be lubricated, a pawl pivotally mounted on the carrier and adapted to coöperate with the ratchet teeth of the drum, a weight arm having a longitudinal slot and horizontally pivoted on the pawl carrier, the pivotal axis extending through said slot, a crescent-shaped rocker coaxially pivoted with the arm and adapted to engage the pawl with one of its horns, said weight having an offset projection adapted to engage the other horn of the rocker in an elevated position and to press the pawl through the intervention of the rocker into engagement with the ratchet teeth, a trigger pivotally mounted on the pawl carrier for releasing the arm from the rocker, and a sliding ring mounted on the drum adjacent to the trigger, having pins extending through slots in the drum, arranged to be

engaged by the carrier when the piston approaches the bottom of the cylinder and adapted to actuate the trigger.

37. An automatic oiler comprising a stationary tubular externally-threaded piston rod, a piston at its lower end, a drum rotatively mounted on the piston rod and having ratchet teeth, a carrier screwed onto the piston rod and slidably mounted within the drum, a cylinder adapted to contain a lubricating fluid, mounted on the carrier with the piston extending downwardly into it, a pawl carrier having a central opening, a ratchet rotatably mounted and having an eccentric cam projection extending into the opening of the pawl carrier and adapted to oscillate the carrier, a pawl mounted on the carrier and adapted to coöperate with the ratchet teeth of the drum for producing a slow rotative movement of the drum and carrier, and a member oscillating in response to the machine to be lubricated and having a pawl adapted to actuate the cam ratchet.

38. An automatic oiler comprising a stationary tubular externally-threaded piston rod, a piston at its lower end, a drum rotatively mounted on the piston rod and having ratchet teeth, a carrier screwed onto the piston rod and slidably mounted within the drum, a cylinder adapted to contain a lubricating fluid, mounted on the carrier with the piston extending downwardly into it, a pawl carrier having a central opening, a ratchet rotatably mounted on said drum, and having an eccentric cam projection extending into the opening of the pawl carrier and adapted to oscillate the carrier, a pawl mounted on the carrier and adapted to coöperate with the ratchet teeth of the drum for producing a slow rotative movement of the drum and carrier, and a member oscillating in response to the machine to be lubricated and having a pawl adapted to actuate the cam ratchet.

39. An oiler comprising a stationary member, a coöperating pressure-producing member, a reciprocating driving member, an oscillatory pawl connected thereto, a rotatable ratchet responsive to the pawl, an oscillatory pawl carrier eccentrically driven by the ratchet, a toothed pressure-producing member, and a pawl mounted on the pawl carrier and coöperating with the pressure-producing member to produce slow rotative movement thereof.

40. An oiler comprising a rotatable drum having interior longitudinal guideways, a yoke adapted to slide in the guideways within the drum and having a tapped hole in its inner end, a stationary tube externally-threaded to receive the yoke, a piston on one end of the tube, and means mounted on the

yoke for supporting a cylindrical container which is adapted to coöperate with the piston.

41. An oiler comprising a discharge nozzle, a stationary piston, a pipe connection between the piston and the nozzle, a check valve in the pipe near the piston, a rotatable drum having ratchet teeth, a yoke mounted to slide in said drum, a fluid container constituting a movable cylinder and adapted to coöperate with the piston, means for actuating the drum, and resilient means for centering the container on the yoke.

42. An oiler comprising a piston, an outlet pipe connected to the piston, a check valve in the pipe, a carrier adapted to be moved in response to the machine to be lubricated, a fluid container constituting a movable cylinder and adapted to coöperate with the piston, and a dove-tailed connector for removably securing the container to the carrier.

43. An oiler comprising a piston, an outlet pipe connected to the piston, a check valve in the pipe, a carrier adapted to be moved in response to the machine to be lubricated, a fluid container constituting a movable cylinder and adapted to coöperate with the piston, and a rotatable stud mounted on the carrier and having a head of dove-tailed section, said container having a dove-tailed groove in its bottom surface to coöperate with the head of the stud.

44. An oiler comprising a piston, an outlet pipe connected to the piston, a check valve in the pipe, a carrier adapted to be moved in response to the machine to be lubricated, a fluid container constituting a movable cylinder and adapted to coöperate with the piston, a rotatable stud mounted on the carrier and having a head of dove-tailed section, said container having a dove-tailed groove in its bottom surface to coöperate with the head of the stud, and means for centering the container on the stud.

45. An oiler comprising a piston, an outlet pipe connected to the piston, a check valve in the pipe, a carrier adapted to be moved in response to the machine to be lubricated, a fluid container constituting a movable cylinder and adapted to coöperate with the piston, a rotatable stud mounted on the carrier and having a head of dove-tailed section, said container having a dove-tailed groove in its bottom surface to coöperate with the head of the stud, and a spring secured in a groove in the stud and coöperating with the cup to center it relative to the stud.

In witness whereof, I have hereunto set my hand this 1st day of June, 1915.

WALTER F. VAN GUYSLING.
